UNITED STATES PATENT OFFICE.

CHARLES KNOPF, OF RICHMOND, INDIANA.

RAILWAY-RAIL FASTENING.

No. 924,908.

Specification of Letters Patent.

Patented June 15, 1909.

Application filed November 19, 1908. Serial No. 463,352.

To all whom it may concern:

Be it known that I, CHARLES KNOPF, a citizen of the United States, residing in Richmond, in the county of Wayne and State 5 of Indiana, have made certain new and useful Improvements in Railway-Rail Fastenings, of which the following is a full, clear, and comprehensive specification, being such as will enable others familiar with the art to 10 which the invention pertains to make and operate the same with exactitude.

My present invention relates to railway rail fastenings which includes metal railway-ties, and the devices substantially as shown 15 for connecting the rails upon the ties.

The object of my invention, broadly speaking, is to produce extremely and highly efficient means for connecting ordinary metal railway rails to metal cross-ties, which means 20 will be strong and durable in construction, positive in action, and which can be produced at a comparatively low price.

More specifically stated, my object is to provide means for connecting railway rails to 25 metal cross-ties, with means for cushioning the rails at each point whereby the desired resiliency will be imparted as traffic passes thereover; to afford means whereby the danger of the rails spreading apart will be 30 substantially *nil*; to afford means whereby the rails may be removed and replaced in a minimum of time and with absolute precision; and affording means whereby the expansion and the contraction of the rails will 35 not be retarded in any particular.

Other objects and particular advantages of my invention will be made apparent in the course of the following specification, and the features which are new will be correlated in 40 the appended claim.

The preferred manner for carrying out the objects of my invention is shown most clearly in the accompanying drawings, in which—

Figure 1 is a perspective view showing my 45 invention in operative position, in connection with a metal tie and portions of two parallel railway rails; Fig. 2 is a sectional view of the parts shown in Fig. 1, as taken on a line extending centrally of and longitudinally through the metal tie; Fig. 3 is an 50 isometrical detail view of one of the four clamping members employed in connection with each tie, for securing two rails thereon; and Fig. 4 is an isometrical detail view of one 55 of the two cushion-blocks for each tie, one being disposed under each of the rails.

Similar indices denote like parts throughout the several views of the one sheet of drawings.

In order that the construction, application, and utilization of my invention may be better understood and appreciated I will now take up a detail description thereof, in which I will define the several parts and the several features as briefly and as comprehensively as I may.

In the drawings the letter A denotes an I-shaped metal tie, similar in cross sectional contour to an ordinary railway-rail, but of larger dimensions. In Figs. 1 and 2 the central portion of the tie is shown as broken away, simply for convenience in drawing. The upper face of the head of the tie A is formed flat, parallel with the under face, and having outwardly extending projections or flanges.

The indices B and B' denote two ordinary railway-rails. As the construction of my improvements is the same for each rail I will describe that for one rail by certain numerals, and refer to like parts for the other rail by like numerals primed or with exponents.

Numerals 1 and 1' denote a flat plate, as of wood or the like, adapted to give the proper resiliency which will increase the life 85 of the rail, will absorb the jar, and will reduce the noise to a minimum. The width of said plate is the same as is the width of the base of the rail B, or B'; its length is slightly more than is the width of the face of the tie A. 90 Said plate has downwardly extending lugs, a and b, one at each end, formed integral therewith, and adapted to fit over the edges of the top or head of the tie, as shown in Fig. 1. Said plate 1 is shown inverted in Fig. 4. Said 95 lugs, a and b, are for the purpose of preventing the plate 1 from slipping endwise out of position. The four clamping members shown are identical with each other.

Numerals 2 and 3 (and 2' and 3') denote 100 the body portion of each of the four clamping members. Said parts are adapted to lie flat on top of the tie, with their sides or edges curved downward and then inward corresponding to the edges of the tie over which 105 they lap, extending inward under the head thereof forming channels for the upper flange edges of the tie to slide in, whereby the clamping members may slide longitudinally along the tie but cannot be removed 110 therefrom, except by sliding them off the ends of the tie. Formed integral with each

of said members 2, 3, 2' and 3', is an upwardly and inwardly directed lug 4, 5, 4' and 5', respectively. The inner face of said lugs is formed of a contour such as to fit and extend 5 up over on the surfaces of the bases of the rails as shown, the inner edges of the members 2—3 and 2'—3' contacting with the sides of the plates 1 and 1' as indicated.

A half-round channel is formed across in 10 the under face of each of the members 2, 3, 2' and 3', as shown in Fig. 2, and more clearly in Fig. 3, which channels terminate at each end in round apertures extending through the curved sides of said members as indicated 15 in Fig. 3. Also a companion channel, for each of said channels, first named, is formed across the upper face of the tie A, as indicated in Fig. 2. The said channels in the face of the tie are so located that they register each with its companion channel in the members 2, 3, 2' and 3' only when the opposed edges of the members 2—3, and 2'—3', are in contact with the plates 1 and 1', as in 20 Figs. 1 and 2, thereby forming a round aperture each for one of the bolts 6, 7, 8 and 9 which, when inserted therein, will manifestly lock each of the clamping members in 25 operative position as shown. In order to prevent said bolts from working out of place 30 there should be a permanent head formed on one end thereof, while the other end may be provided with a threaded nut, or preferably with a spring key disposed at right-angles therethrough, as indicated by the numerals 35 10, 11, 12 and 13, for the respective bolts. It will be noticed that the clamping members are arranged in pairs, two pairs being 40 located on one tie, each pair engaging a different rail, and the two members of each pair are oppositely disposed with relation to each other.

Desiring to remove the rails one has only to remove one of the bolts and slide the clamping member thereof back from engagement with the rail, but not removing said member from the tie, this being done only on one side of the rail at each tie on which the rail rests after which, it is manifest, that the rail may be skidded to one side removing it 45 from the cushion-block and from engagement with the other (secured) clamping member.

In placing the rails the reverse of the above operation is made: One member of each pair

of clamping members is secured in position, all facing in the same direction, the cushion- 55 plates are then placed in position, after which the rail is positioned on said cushion- plates, and the other member of each pair of clamping members is then slid up to position and they are secured by their respective bolts, 60 which will, of course, complete the operation and retain the rails in position as shown.

I desire that it be understood that various changes may be made in the details of construction, herein shown and described, without departing from the spirit of my invention or sacrificing any of the advantages thereof.

Having now fully shown and described my invention, what I claim and desire to secure 70 by Letters Patent of the United States, is—

In combination with a railway rail, and a metal cross-tie having an upper flanged head and a flat base, a pair of oppositely directed clamping members for each rail slidably 75 mounted on the tie and removable therefrom only at the ends of the tie, said clamping members having their sides curved downwardly and then inwardly to engage the edges of the tie and forming channels for the 80 upper edges of the tie to slide in, an upwardly and inwardly projecting lug formed on each of said clamping members and adapted to engage the surfaces of the base of the rail, a bolt for each of said clamping members, there 85 being channels formed across in the upper face of the tie and a companion channel for each formed across in the under face of each of said clamping members forming an aperture for said bolt, a key for retaining the bolt 90 in position, and a cushion-block disposed between the under face of the rail and the upper face of the tie, the ends of said block being turned down at right angles to the block to engage the edges of the tie to retain 95 the block in position, all substantially as shown and described and for the purposes set forth.

In testimony whereof I have hereunto subscribed my name to this specification in 100 the presence of two subscribing witnesses.

CHARLES KNOPF.
